TENSIONING MEANS FOR FLAT KNITTING MACHINES

Peter J. Schoenster, Teaneck, N.J., assignor to Alfred Hofmann & Co., West New York, N.J., a corporation of New Jersey

Application January 16, 1956, Serial No. 559,418

7 Claims. (Cl. 66—86)

This invention relates to improved means for tensioning the yarn sheet of a flat knitting machine, as such sheet moves in a path between the yarn supply beam and the knitting elements of the machine.

In conventional arrangements for tensioning the yarn sheet, it is common to use an oscillatory bar which extends the length of the machine and has arms extending therefrom for mounting a tension rod over which the yarn sheet passes, together with spring loading means abutting levers extending from the bar. In this manner, tension is provided to keep the yarn sheet taut during the knitting cycle. However, the spring loading means, which usually takes the form of an elongated compression spring, is operative to provide for a wide range of up and down movements of the tension rod.

Furthermore, such conventional yarn tensioning arrangements are also used to actuate braking mechanisms which control the rotation of the yarn supply beam, and hence, the flow of yarn from the beam, as typically shown in Patent 2,395,807, 2,521,218, etc., assigned to the assignee of the instant application. Under such circumstances, it is desirable that the tension rod have a wide range of fluctuation in its up and down movements, in order to allow optimum operation of the braking mechanism so as to provide a yarn flow which is as constantly equal as such control means will permit.

With the use of the elongated compression springs mentioned above, there are set up vibrational forces which are detrimental to the accurate control of the tension of the yarn sheet. The advent of modern, high speed knitting machines, particularly the tricot type, made it desirable to improve the control of the movement of the yarn sheet from the yarn supply beam. Such improved control means may take the form of a positive drive for the beam and control means for the drive, as shown in Patent 2,707,380 assigned to the assignee of the instant application.

While attempts have been made to effect improvements in the yarn tensioning means, as by connecting the tension rod to the bar by flat springs and fixing the bar against oscillatory movement, such arrangements which still have a wide range of fluctuations in the up and down movement of the tension rod, result in snarling of the yarns, as well as faults in the knitted fabric such as shade marks, pin holes and the like.

Accordingly, an object of this invention is to provide improved means for tensioning the yarn sheet in a flat knitting machine, which includes in addition to the usual spring means allowing a wide range of fluctuations in the movement of the tension rod, auxiliary means for limiting the overall operating range of the tension rod in accordance with precision tension requirements of the yarn as dictated by the composite, related motion of the needles, sinkers and yarn guides of the machine, in relation to the yarn supply.

Another object of this invention is to provide improved yarn tensioning means of the character described, for use

2

in machines having positive yarn feeding means operative to supply a constant length of yarn predetermined by the quality of the fabric being knitted, such tensioning means being operative to provide suitable tension commensurate with changes in the yarn length temporarily occasioned by the motions of the knitting elements of the machine.

A further object of this invention is to provide improved yarn tensioning means of the character described wherein the auxiliary tension means comprises resilient means having high frequency reactivity, for use with high speed knitting machines.

Still another object of this invention is to provide improved yarn tensioning means of the character described, wherein the auxiliary tensioning means may be adjusted in a manner to vary the operating range thereof.

Other objects of this invention will in part be obvious and in part hereinafter pointed out.

In the drawing,

Fig. 1 is a schematic showing of conventional means known in the art for controlling the tension of the yarn sheet between the yarn supply beam and the knitting elements of a flat knitting machine;

Fig. 2 is a diagrammatic showing of yarn tensioning means embodying the invention; and

Fig. 3 is a diagrammatic showing of a modified form of the invention.

Referring in detail to the drawing and particularly to Fig. 1, 10 designates conventional means, well known in the art, for tensioning the yarn sheet in a flat knitting machine. The same comprises an elongated bar 11 mounted in suitable bearings along the length of the knitting machine, for oscillatory movement. A tension rod 12 extends parallel to bar 11 and is rigidly attached thereto by spaced arms 13. Levers 14 extend from bar 11 in a direction opposite to that of arms 13, with elongated compression springs 15 extending at right angles to said levers and abutting the same. Springs 15 are mounted on rods 16 which are attached at their lower ends to the machine frame, as at 17. The free ends of rods 16 are threaded as at 18 to receive nuts 19 for adjusting the compression of springs 15 as the same abuts levers 14.

As the yarns Y move from the yarn supply beam 20 toward the knitting elements indicated at 21, they pass over the tension rod 12; the springs 15 being operative to keep the yarns Y taut during the knitting cycle. It will be apparent that the rod 12 has a wide range of up and down movement within the compression limits of springs 15. The movement of the tension rod 12 may also be used to actuate brake mechanism, not shown, for controlling the rotation of the beam 20 and thus, the flow of yarns Y.

With the advent of high speed knitting machines operating at 1,000 c.p.m. or more, and with the use of mechanisms for positively driving the yarn beams to supply a predetermined linear length of yarn to the knitting elements, in timed relation to the knitting speed of the machine, as typically shown in Patent 2,707,380, it is essential that a more precise control of the yarn tension be maintained in order to obtain knitted fabric free of defects.

Thus, with knitting machines having such positive beam drives, the yarn tensioning means has primarily the function of following the motions of the knitting elements of the machine. As is well known, in the formation of a loop, there is required a composite related motion of the needles, sinkers and yarn guides, which, by their respective motions, require a temporary following of yarn, in addition to the length of yarn supplied for the specific loop construction.

Such additional following of yarn supplied to the knitting elements in the course of the knitting cycle, is

provided by the operation of the tension rod as the same yields in response to compression of the springs described above. However, it is noted that the temporary requirement for yielding additional yarn, is rather limited in comparison to the degree of yield of the tension rod as afforded by the conventional spring arrangements indicated above. It follows that such known yarn tensioning means does not lend itself to optimum performance when used in conjunction with automatic yarn feed means which deliver constant lengths of yarn to the knitting elements.

Accordingly, there has been provided auxiliary tension means operating in conjunction with the main tension means, and operative to limit the operating range of up and down movements of the tension rod during knitting operations. To this end there is provided auxiliary resilient means in the form of rubber or spring elements having high frequency reactivity which is quickly responsive to the yarn requirements during the knitting cycles of high speed knitting machines.

Thus, as shown in Fig. 2, the improved yarn tensioning means 10a embodying the invention, comprises the oscillatory bar 11 with tension rod 12 fixed thereto by spaced arms 13 extending transversely thereof, a single arm 13 being shown. A lever 14 extends transversely from bar 11 away from arm 13. A tension spring 15a is anchored at one end to the machine frame at 17a and is connected at the other end to lever 14, thus supplying tension for the yarns Y moving from yarn supply beam 20a over tension rod 12 to the knitting elements, as previously described.

Preferably, yarn supply beam 20a is positively driven by a gear arrangement 22 operated by suitable speed control means generally indicated at 23. Such positive drive may take the form of variable speed mechanisms interposed between the main cam shaft of the knitting machine, not shown, and the gear arrangement 22 and responsive to changes in the diameter of the beam 20a, all as detailed in Patent 2,707,380; and being operative to provide a constant linear feed of yarn to the knitting elements of the machine.

Primarily, spring 15a is effective to prevent an undue loosening of the yarns in yarn sheet Y in its movement to the knitting elements, as may be occasioned by an excessive supply of yarn for the specific fabric construction to be knitted, or as a safety means for taking up excessive yarn in the event of an accidental overdrive of the yarn supply beam 20a. It is understood, that for safety purposes, a micro-switch, not shown, in circuit with the motor drive of the machine, may be suitably located for actuation in response to excessive movement of the tension rod 12 in either direction to points beyond the normal operating range thereof, to automatically stop the machine.

Additionally, yarn tensioning means 10a comprises a resilient member 24 in the form of a rubber cushion slidably mounted on a rod 25, which rod is attached at one end thereof to the machine frame. The cushion 24 abuts lever 14; the rod 25 passing through an opening 26 in said lever. The rod 25 is threaded at the other end thereof and a nut 27 is screwed on the threaded portion of the rod, with the cushion 24 fixed to said nut to allow the cushion to be adjustably positioned relative to lever 14.

It will be apparent that the downward movement of tension rod 12 will be limited by the compressability of cushion 24. Thus, during the knitting cycle, yarns from sheet Y will flow in response to the high frequency reactive tensioning action caused by the abutment of lever 14 against cushion 24. The axial length of cushion 24 is sufficient to provide the necessary yield of tension rod 12 to follow the required temporary yield in the yarns in response to the momentary needs of the knitting motions over and beyond the current supply of yarn.

required for the formation of the successive loops and courses of the knitted fabric.

It is understood that in the arrangement shown in Fig. 2, a short compression spring or other resilient member having the proper high frequency reactivity, may replace rubber cushion 24. Also, an elongated compression spring may be used in lieu of tension spring 15a, as suggested in Fig. 1.

The instant invention may also be embodied in the form shown in Fig. 3, wherein the cushion 24a is mounted on the downwardly extending arm 28 of a right angle bracket 29 attached to a portion 30 of the machine frame. Oscillatory bar 11, with associated tension rod 12, arms 13 and levers 14, is located so that levers 14 are disposed in opposed relation to cushions 24a and abut the same as tension rod 12 moves downwardly against the action of tension spring 15a interconnecting the outer end of lever 14 and frame portion 30.

Preferably, cushion 24a may be mounted in adjusted positions along bracket arm 28, by means of a threaded member 31 extending from said cushion and receivable in openings 32 formed along said bracket arm and retained in place by nut 33. With the position of cushion 24a as indicated in solid lines, the leverage action between arms 13 and levers 14 is in the ratio of about 1:1, whereby if cushion 24a is compressed axially to the extent of about $\frac{1}{8}$ ", tension rod 12 will yield under a given tension load of the moving yarns of about $\frac{1}{8}$ ".

However, if cushion 24a is moved to a lower position on bracket arm 28, as indicated in dotted lines, abutment of lever 14 will occur at a point equal to about $\frac{1}{3}$ of the length of said lever. Thus, with a compression of cushion 24a of the order of $\frac{1}{8}$ ", there will be provided a leverage range in the motion of tension rod 12 amounting to about $\frac{3}{8}$ ".

It is thus possible to change the operating range of the yarn tensioning means as may be required by the knitting details of different types of fabrics and yarns, yet providing suitable auxiliary means for precisely and more effectively determining and limiting the overall operating range of the tension rod of the knitting machine.

It is understood that levers 14 and associated spring means and high frequency reactive resilient means associated therewith may be provided at the opposite ends of the oscillatory bar 11. Furthermore, the yarn beam supply may be positively driven by any suitable means to impart a desired linear speed to the yarns Y as they move over the tension rod 12 to the knitting elements 21.

As various changes might be made in the embodiments of the invention herein described without departing from the spirit thereof, it is understood that all matter herein shown or described shall be deemed illustrative and not by way of limitation except as set forth in the appended claims.

Having thus disclosed my invention, I claim as new and desire to protect by Letters Patent:

1. In a knitting machine, tensioning means for the yarns comprising an oscillatory bar, a tension rod extending parallel to said bar, means for rigidly and immovably fixing said rod to said bar for conjoint movement, lever means projecting laterally from said bar, spring means operatively related to said lever means for controlling the oscillatory movement of said bar in response to variations in tension of yarns moving over said rod, and auxiliary resilient cushion means operatively engageable with said lever means for limiting the range of movement of said oscillatory bar.

2. A knitting machine as in claim 1 and further including means for mounting said auxiliary resilient means in adjusted positions relative to said lever means.

3. A knitting machine as in claim 2 and further including means for adjusting the position of said auxiliary resilient means relative to the longitudinal extent of said lever means to vary the leverage ratio between

said lever means and the means fixing the tension rod to said bar.

4. In a knitting machine, tensioning means for the yarns knitted by said machine comprising an oscillatory bar, a tension rod, means connecting said bar and rod in parallel relation, lever means extending laterally from said bar, spring means for controlling the oscillatory movement of said bar, and high frequency responsive resilient rubber cushion means located opposite said lever means for abutment thereby to limit the oscillatory movement of said bar.

5. Yarn tensioning means for a knitting machine comprising a bar mounted on the frame of the machine for oscillatory movement, a tension rod extending parallel to said bar, means for fixedly attaching said rod to said bar, lever means extending laterally from said bar, bracket means on the frame of the machine including an arm fixedly located opposite said lever means, high frequency reactive resilient means mounted on said bracket arm for abutment by said lever means upon oscillatory movement of said bar, and resilient means connecting said lever means and the frame of said machine for controlling the oscillatory movement of said bar.

6. Yarn tensioning means as in claim 5 and further including means for locating said first mentioned resilient means in adjusted positions along said bracket arm.

7. Yarn tensioning means for a knitting machine comprising a bar mounted on the frame of the machine for oscillatory movement, a tension rod extending parallel to said bar, means for fixedly attaching said rod to said bar, lever means extending laterally from said bar, spring means operatively related to said lever means for controlling the oscillatory movement of said bar, means for locating high frequency responsive resilient means in the path of movement of said lever means for abutment thereby, and means for adjusting the position of said resilient means to vary the distance thereof relative to the pivotal point of said lever means.
